MILTON A. POWERS, OF DETROIT, MICHIGAN, ASSIGNOR TO THE TIMKEN SILENT AUTOMATIC COMPANY, OF DETROIT, MICHIGAN, A CORPORATION OF MICHIGAN

OIL BURNER WITH SUPPLEMENTARY AIR INTAKE

Application filed November 30, 1931. Serial No. 577,882.

My invention relates to air intakes for oil burners and has for its object an improvement in supplying air for combustion on installations where the rate of burning is above 5 the normal capacity of the burner. It is well known that the vertical rotary type of oil burner, wherein combustion occurs around the periphery of a hearth ring, is capable of a wide range of operating capacity with good 10 combustion quality and high operating efficiency. This fact enables a burner of comparatively small size to be applied to a wide range of boiler sizes. However, in view of the fact that most installations require but a 15 low rate of combustion, it is impractical and the cost of production is too great to build all units of the same potentially high capacity when it is known that but a few will be operated at those high capacities. Likewise it 20 is not desirable to build a larger size burner in small numbers if the smaller unit can easily be adapted for such use.

Assume that a small burner of this type is quite capable of handling combustion rates 25 up to, for example, 35 pounds of oil per hour. Above said rate, depending of course upon the specific design of the unit, the air supply will become restricted and, although a larger amount of oil may pass through the burner 30 and be properly placed, it will be impossible to burn it efficiently due to a lack of air.

In the past such deficiency at higher rates has been overcome by inserting a number of 35 openings in the hearth surface through which additional air might be induced by the below atmosphere pressure conditions in the firebox. This method, while widely used, was not very effective and had numerous disadvantages. In the first place, as the additional air supply 40 was entirely controlled by draft conditions, it was impossible to maintain a constant air supply to match the constant oil feed to the firebox. When the draft was high, too much air entered and when the draft was 45 low, too little air was supplied for proper burning. Too much air being the lesser of the two evils, field practice has always been to provide for a large excess air rate with the old method. Secondly, the old method of 50 supplying auxiliary air prevented the main

air supply from having the proper direction and velocity; because the air flow through the hearth openings was upward rather than outward and this upward flow of air interfered with that coming from the fan, preventing proper mixing at the edges. This is an important disadvantage, since the direction and velocity of the air stream on a rotary type burner is very important: as combustion takes place only around the periphery of the 60 hearth, it is essential that the air be directed to the edge in proper quantity and with sufficient velocity to mix with the oil vapors and burn completely. This is particularly important on large installations where the distance from the burner head to the hearth ring 65 is large. In the third place, the openings were unevenly placed and the proportioning of air and oil was not constant around the periphery. In the fourth place, the hearth 70 openings were hard to make, generally consisting of pipe nipples connected in place, with the number installed, and the number plugged shut during adjustment being entirely up to the judgment of the service man. 75

None of the above disadvantages exists with the present invention and much improved operation results when it is used, as will be presently evident. It provides an auxiliary air supply that is easily regulated 80 and that does not interfere with the proper functioning of the burner.

In the accompanying drawing, Fig. 1 is a perspective view of an oil burner with a supplementary air intake embodying my invention, Fig. 2 is a detail view of a ring for varying the amount of auxiliary air, and Fig. 3 is a partial vertical sectional view, parts of the burner being shown diagrammatically.

An annular casting 1 is provided with 90 internal supporting fins 2 which carry its weight when dropped in place over the head of a standard burner, said fins 2 resting on a portion 3 of the usual burner-frame 4. The casting 1 is provided with an outwardly extending annular bottom flange 5, upon which the hearth pan 6 is carried and the hearth proper 7 built. The weight of the hearth is then carried by the burner in the conventional manner, the fins 2 on the intake ring 1 trans- 95 100

mitting the weight to the burner frame 4. With the ring 1 in place it will be noted that an annular space 8 exists between said ring and the outside of the burner frame 4.

5 This space plus the capacity of the burner is sufficient to provide air for the maximum desired capacity. When less auxiliary air is required (and in all cases it is desirable to use as much fan air as possible due to its 10 higher initial velocity) the intake area may be reduced by dropping in place in said annular space 8, one of several sizes of adjustment rings 9, said ring resting on the top of the burner frame 4. Thus accurate control 15 of the amount of auxiliary air supply is possible. The largest adjustment ring 9 substantially fills the annular space 8 between the top of the burner frame and the inner periphery of the casting being provided with 20 notches 10 to accommodate said fins. Of course, this largest ring, since it practically closes off the entire area, is used only when conditions after installation indicate no need for an auxiliary air supply and ordinarily 25 some smaller size ring is required.

This intake construction causes the air to enter in close proximity to the lower edges of the fan 11. While the fan body has a diameter approximating that of the burner 30 frame (4) the blades themselves being of higher capacity extend outward a considerable distance, projecting largely if not entirely over the annular area of the auxiliary air supply (8). As is well known, a definite 35 negative air pressure exists just below the lower edges of fan blades of this type particularly where the air flow into the fan proper requires redirecting as in this case. The fan thus induces a large air flow through 40 the auxiliary intake, the amount of this flow being relatively constant and but little influenced by draft variations. My intake therefore allows accurate adjustment of the air flow which thereafter is practically un- 45 affected by outside variables.

The auxiliary air blends in with the main air flow and the two travel together at the proper velocity and in the proper direction for best mixing and combustion at the hearth 50 ring. This is in direct contrast to the interference and improper flow of the air with the old method described above. In addition my design assures a properly proportioned air feed to all portions of the hearth.

55 As the annular casting requires practically no effort to install, the saving in labor is considerable, while the resulting assembly is workmanlike in appearance and its effectiveness depends in no way upon the ability of 60 the workman making the installation. The air adjustment by use of the proper size restricting ring is readily accomplished and when once determined will not require further attention.

65 It is clear that the invention is capable

of modifications in the details of construction without altering its essential character. Therefore, I do not wish to be limited to the precise construction shown.

What I claim is:

1. A rotary oil burner comprising a frame, a fan rotatably mounted at the top of said frame, an annular member resting upon said burner frame and providing therewith an annular supplementary air intake and a hearth member supported on said annular member, said annular air intake being outside the burner frame in proximity to the lower edge of said fan member the blades of said fan overhanging a substantial portion of said annular air intake.

2. A burner frame, a distributor head supported therein and including a fan projecting above said frame and arranged to spray oil and air outwardly, an annular casting supported on a portion of said burner frame and forming an annular air intake space between it and the top portion of said frame, adjacent to the lower edge of said fan and a ring supported on the top of said frame in said annular space, whereby the size of said space may be varied by substituting a ring of different size.

3. A burner frame, a distributor head supported therein and including a fan projecting above said frame and arranged to spray oil and air outwardly, an annular casting supported on a portion of said burner frame and forming an annular air intake space between it and the top portion of said frame, adjacent to the lower edge of said fan and a ring supported on the top of said frame in said annular space, whereby the size of said space may be varied by substituting a ring of different size, the blades of said fan overhanging a substantial portion of said annular air intake.

Signed at Detroit, Michigan, this 20 day of November 1931.
